UNITED STATES PATENT OFFICE.

ROY VINSON COLLINS, OF WEST NEWTON, MASSACHUSETTS.

SWITCH-OPERATING MECHANISM.

1,254,122.

Specification of Letters Patent. Patented Jan. 22, 1918.

Application filed March 9, 1915. Serial No. 13,148.

To all whom it may concern:

Be it known that I, ROY VINSON COLLINS, of West Newton, in the county of Middlesex, and in the State of Massachusetts, have 5 invented a certain new and useful Improvement in Switch-Operating Mechanism, and do hereby declare that the following is a full, clear, and exact description thereof.

The object of my invention has been to 10 provide a mechanism for and method of operating switches whereby the switch of a railroad of any type, but particularly a trolley railroad, can be thrown, by electric mechanism, under the control of the motor-man and without stopping the car or train, which shall have, among others, the following advantages:

That it shall involve the use only of cheap and simple contactors on the trolley wire, 20 and especially of contactors not using any magnet or other form of electric motor thereon.

That it shall permit the electric motor for 25 operating the switch point to be put in a sealed box in the ground, since it avoids the making of arcs in the motor box.

That while it shall provide a motor mechanism for operating the switch point, it shall also permit the switch to be thrown 30 by hand, thus permitting the correcting of an error in throwing the switch, without requiring the backing of the trolley car.

That it shall be so arranged that the motor shall pick up its full load only in successive portions, thus permitting the use of a lighter motor than would be possible otherwise.

And to such ends my invention consists 40 in the mechanism for and method of operating switches hereinafter described.

In the accompanying drawings:—

Figure 1 is a diagrammatic view showing 45 an apparatus embodying my invention, with parts in normal position, that is, with the motor at rest and the parts ready to be operated by an approaching car;

Fig. 2 is a view similar to Fig. 1, showing 50 a trolley passing under the first and second contactors with the motor current off, and in engagement with the second contactor;

Fig. 3 is a view similar to Fig. 1, showing 55 a trolley passing under the third contactor, which causes the operation of the throw-off

device by which the circuit to the motor is 55 broken and the parts caused to be restored to normal position;

Fig. 4 is a view similar to Fig. 1 showing 60 a trolley passing under the first contactor with the motor current on and the current flowing through the trolley, owing to the completion of the circuit, due to the position of the motorman's controller;

Fig. 5 is a plan view of the motor and 65 switch operating parts;

Fig. 6 is a side elevation of the parts shown in Fig. 5;

Fig. 7 is a section on line 7—7 of Fig. 5 looking in the direction of the arrows; and

Fig. 8 is a section on line 8—8 of Fig. 5, 70 looking in the direction of the arrows.

While I have illustrated my invention by the best embodiment thereof known to me, such embodiment is to be regarded as typical only of many possible embodiments and 75 uses, and my invention is not to be restricted thereto.

In general, my apparatus consists of a first and second contactor preferably located on the trolley wire or other car motor current conductor with which the trolley or other collector of the motor-car is to come in contact, to cause the switchpoint to be thrown to proper position, if not already in proper position. The position to which 85 the switchpoint is thrown is determined by whether or not the motor current on the car is open or closed. Such contactors are located a sufficient distance ahead of the switch so that, although the car may be moving 90 rapidly, the mechanism will have time to throw the switch before the car reaches it and yet will not have to operate so quickly as to cause the switch to splash any water that may cover its parts, thus causing injury to the clothing of a passer-by.

A third contactor is located on the trolley wire or other conductor at a point so located with respect to the switch point that the trolley wheel will not pass under such 100 contactor until the last wheel of the car is on the switchpoint, thus preventing the throwing of the switchpoint after the front wheels have passed it and before the rear wheels have reached it.

I mount upon the trolley wire a first contactor comprising an insulated section 1 of conductive material and have shown it dia-

grammatically as supported by a section of non-conducting material 1^a mounted upon the trolley wire. Parts 1^b and 1^c are mounted upon the trolley wire but insulated from the part 1, the said parts 1^b and 1^c serving, respectively, gradually to remove the trolley wheel from the trolley wire and depress it to the level of the part 1, and again to take it from the level of the part 1 and restore it to the trolley wire, so that the trolley wheel may, by a comparatively smooth motion, run under the part 1. A wire, to be later described, connects the insulated section 1 with the trolley wire through certain contact devices to be later described.

Beyond the insulated section 1 is a second contactor consisting of a frame 2 supported on the trolley wire and having a lever 2^a pivoted thereto on a pin 2^b. Said lever has ears 2^c between which a movable contactor 2^d is pivoted on a fulcrum-pin 2^e. The frame carries a stationary contact 2^f mounted on an insulating block 2^g. The movable contact has a shoulder 2^h which normally rests on a bearing plate 2ⁱ on the frame. When, however, the lever 2^a is raised by the trolley wheel, the shoulder 2^h is raised off the bearing plate 2ⁱ, and the movable contact 2^d is allowed to fall on the stationary contact 2^f. The frame and lever are in electrical connection with the trolley wire, so that this action conducts the trolley current to the stationary contact 2^f. The stationary contact 2^f is connected by a wire 3 with a stationary contact 4, to be later described.

In the drawings are shown diagrammatically two movable contact devices which, in the illustrated embodiment, are represented as levers, one or the other of which is thrown into operative position according as the trolley passes under the insulated section 1 of the first contactor, and the lever 2^a of the second contactor, with the motorman's controller in the position, respectively, to permit or not to permit the flow of current through the trolley. These contact levers are adapted to make operative connections with stationary contacts of which, in the present instance, there is a vertical row numbered from top to bottom respectively, 5—6—7—8—9—10—11—12—13 and 14. There are also the before-mentioned contact 4 and a contact 15 which are adapted to be engaged by contact lever 16 in its retracted position. There are also stationary contacts 17 and 18 which are adapted to be engaged by the contact lever 19 in its retracted position. The lever 16 carries an armature 20 which is adapted to be attracted by a relay magnet 21 which raises it and throws the lever 16 into contact with the vertical row of contacts; and the lever 19 carries an armature 22, which is similarly adapted to be attracted by a relay magnet 23, so as to throw the lever 19 into contact with the ver-

tical row of contacts. The weight of the armature 20 is the means used in the present instance to retract the lever 16 and keep it normally in contact with contacts 4 and 15, and similarly the weight of the armature 22 is used to retract the lever 19 and keep it normally in contact with the stationary contacts 17 and 18. The levers 16 and 19 are provided with conductive portions shown in white, which are insulated from each other and from the levers by the insulating material shown in black. I will not describe the wiring connected with the various stationary contacts operated by the levers 16 and 19 in advance of the description of the operation of the device, as such wiring can be understood with less effort in connection with the description of said operation.

Stationary contacts 23^a and 24 also are provided which are adapted to be connected by a contact device, in the present instance shown as in the form of a lever 25, said lever having an armature 26 which, when attracted by relay magnet 27, removes the lever 25 from the contacts 23^a and 24, this, as later described, interrupting current through the relay 21 or 23 (whichever one may be in operation), permitting the lever 16 (or 19) then in use to fall back to normal position. The relay 27 is controlled by a third contactor 28 which is in all respects similar to the second contactor above described, and which has a lever 28^a corresponding to the lever 2^a of the second contactor, a stationary insulated contact 28^b corresponding to the contact 2^f and a movable contact 28^c corresponding to the movable contact 2^d. The connections of the third contactor will be described later.

The switchpoint is moved by mechanism, 105 to be later described, operated by a motor having an armature 30 whose commutator has a brush 31 connected by a wire 32 with the stationary contact 6, and whose commutator also has a brush 33 connected by a 110 wire 34 with the stationary contact 8. The field coils 35 are connected on the one side by a wire 36 with contact 7, and on the other side with the ground 37.

The motor and switchpoint-operating parts are preferably mounted in a box made water-tight by a mercury seal, said box being preferably on a level not substantially higher than said switch. The motor shaft carries a wheel 38 engaging a worm-rack 39 on a bar 40, the latter being mounted in any desired manner. The said bar carries a pin 41 which is illustrated as provided with an anti-friction wheel 42 that is adapted to engage an arm 43 on a shaft 44. The shaft 44 transmits motion to the switchpoint by means to be later described and the arm 43 preferably is connected with the shaft 44 so as to permit a movement of the arm to some extent before any movement of the 130

shaft takes place. In other words, there is lost motion connection between the arm and the shaft. This connection is, in the present instance, provided by passing a bar 45 through the shaft, the bar occupying slots 46 in the arm, which slots are wider in the plane of motion of the arm than the bar 45, thus permitting the lost motion. Cotter pins 47 in the ends of the bar maintain it 10 in place.

The shaft 44 (which is mounted in stationary bearings) carries on its upper end an arm 48 which is to transmit motion to the switchpoint. The arm 48 has a hole or slot 15 in which is received a pin 49 carried by a sleeve 50, the latter being mounted to slide on sleeves 51 and 52 which are threaded upon a rod 53 that is pivoted to a bar 54 attached to the switchpoint.

20 The sleeves 51 and 52 have shoulders 51^a and 52^a respectively which are adapted to be struck by the opposite ends of the sleeve 50 to shift the rod 53 and, by means of it, the switchpoint. The sleeves 51 and 52 are adjustable 25 on the rod 53 by reason of their threaded engagement therewith and they are locked in position as by locknuts 55 and 56 respectively.

At this point the mechanical operation of 30 the motor and of the parts transmitting motion therefrom to the switchpoint will be described, in order that the description of the apparatus as a whole may be made more concise when that is given. When the motor 35 circuit is completed, the motor revolves, carrying with it the worm 38. The first tooth of the rack is pressed against the worm-wheel by the action of an arm 57 carried by a counter-weight 58 that is mounted on a 40 stationary pivot, said arm 57 engaging a shoulder 59 on the rack. This yielding pressure, due to the counter-weight, holds the said first tooth against the side of the worm ready to be engaged by the worm upon its 45 next turn around and the successive teeth of the rack are then engaged by the worm-wheel until the entire rack has passed by the worm-wheel, when the latter is free to turn in a blank space beyond the last tooth of 50 the rack. The arm 57 now being engaged by a shoulder 60 on the rack, the travel of the rack having caused the said shoulder to swing the arm 57 to the opposite side of its pivot from that side which it occupied when 55 it was engaged by the shoulder 59, the one counter-weighted arm now serves to press the last tooth of the rack yieldingly against the worm-wheel in a position so that, when the motor is reversed, the said last tooth will 60 be engaged by the worm and the rack caused to travel past the worm-wheel in the opposite direction. When the rack moves to the left, the roller 42 engages the arm 43 and swings it to the left, causing it to turn the 65 shaft 44 and the arm 48, the latter moving

the sleeve 50 and causing it to strike against the shoulder 52^a and swing the switchpoint to the left.

I desire that between the operations of the motor—that is, when the rack is in either extreme position, the switchpoint shall be disconnected from the operating mechanism, so that it can be thrown by hand if desired, thus making it unnecessary for the trolley car to back up and operate the first 75 or second contactor again in case the motorman should pass under the contactors with his controller in the wrong position and, hence, throw the switchpoint in the wrong direction. For this purpose, I cause the 80 roller 42 to travel far enough or, conversely, the arm 43 to be short enough, so that when the rack has traveled to its extreme left position, the roller 42 has passed beyond the end of the arm 43, thus effecting a mechanical disconnection of the switchpoint, for the purpose of leaving the switchpoint free to be moved by hand. In order that the roller 42 may engage the lever 43 when the rack begins to travel to the right, I provide means 85 to swing the lever 43 to the right after its release from the roller 42, so that its end will stand in the path of travel of the said roller. In the present embodiment such means consist of a counter-weight 61 carrying an arm 62 which plays between shoulders 63 and 64 on the arm 43. When the lever 43 is forced to the left by the travel of the roller 42, its shoulder 63 is brought in contact with the arm 62 and the said arm is 90 moved to the left against the pull of the counter-weight. As soon as the lever 43 is disengaged from the roller 42, the counter-weight causes the arm 62 to throw the said lever to the right, when it will be in position 95 to be engaged by the roller 42 upon its return travel. Similarly, when the roller 42 approaches its right-hand extreme position, it again passes beyond the end of the arm 43 and the latter is released from the roller 100 105 and is caused to swing to the left by the action of the arm 62 against the shoulder 64, so as to be in position to be again engaged by the roller 42 upon its return stroke.

The swinging of the arm 43 in the manner 115 above described places it in position to be engaged by roller 42 and swung to rotate shaft 44 and arm 48. The swinging of the arm 48 reciprocates the sleeve 50 and causes it, by striking against the shoulders 51^a or 120 52^a, to reciprocate the parts connected with the switchpoint. I desire to provide lost motion between the arm 48 and the switchpoint, so that the motor will not have to move the switchpoint until after it has started to move the shaft 44 and arm 48, thus permitting the motor to get substantially all the parts, but the switch parts, into motion before it has to take up the load of the switchpoint and its immediate parts. The 130 125

adjustability of the shoulders 51^a and 52^a enables me to do this, and yet to move the switchpoint accurately.

I now will describe the mode of operation 5 of the apparatus, and in doing so the connection and operation of the various wires will be clear.

As before stated, the manner in which the motorman controls the switch to determine 10 whether his car shall take the curve or go straight ahead is to have the motor-current on or off, in the one instance, or the other, as he passes the first and second contactors.

In the present instance, it may be assumed 15 that the apparatus is so constructed that if the motorman passes under the first and second contactors with the current on, the switch will be set for the curve, if it is not already so set, and if he passes under such 20 contactors with the current off, the switch will be set for the straight track, if it is not already so set.

Assuming, first, that the motorman wishes to set the switch for the straight track: He 25 will approach the first contactor with the current off in the motors of the car, and as the trolley wheel passes on to the insulated section 1 of such contactor, there will be no motor current being drawn through the car, 30 but when the trolley wheel comes in contact with the pivoted lever 2^a (Fig. 2) the said lever will be moved upward by reason of the upward pressure of the trolley wheel and a circuit will be completed from the moving 35 contact 2^a (which is electrically a part of a trolley wire), through stationary contact 2^c, along wire 3 to contact 4, through contact-lever 16 to contact 15, thence along wire 65, through relay 23, wire 66, and resistance 67 40 to the ground 68. This will cause relay 23 to be energized and to lift armature 22 and move lever 19 into engagement with the vertical row of contacts. This action will complete a circuit through the said relay 23 for 45 holding the lever 19 in engagement with the vertical row of contacts, after the trolley wheel has passed from under the lever 2^a, and consequently, after the movable contact 2^a has ceased to touch the stationary contact 2^c. The said circuit (which I may term a "maintaining" circuit) is as follows:

It extends from the trolley wire, through 50 fuse 69 (at the right, Fig. 2), along wire 70 to contact 23^a, and thence through lever 25 to contact 24, and by wire 71 to contact 11, through lever 19 to contact 12, by wire 72, through relay 23, along wire 66, through resistance 67, and to the ground 68. While 55 the lever 19 is in engagement with the vertical row of contacts, a circuit will be completed through the switch operating motor, as follows:

From the trolley wire through the fuse 69, 60 wire 73, resistance 74, wire 83, contact 5, lever 19, contact 6, wire 32, through the

armature 30 of the motor and by wire 34 to the contact 8, through the lever 19 to the contact 7, and thence by wire 36 through the fields 35 of the motor and to the ground 70 75 37. This will cause the motor to rotate in the direction for throwing the switch for the straight track, and after the switch has been so thrown the motor will continue to revolve, although the last tooth of the rack having passed beyond the worm, the switchpoint will be free to be thrown by hand if the motorman has made a mistake. When the trolley wheel passes to the third contactor the lever 19 will be restored to normal retracted position in the following manner: 80

A circuit will be completed by reason of the upward pressure of the trolley wheel on the lever 28^a (Fig. 3) causing the movable contact 28^c to engage stationary contact 28^b, thus permitting the trolley current to flow 85 through the said lever and movable contact to the stationary contact, and thence along wire 75, through relay 27, by wire 76, through resistance 67, to the ground 68. This will cause relay 27 to attract armature 90 26 and throw lever 25 to the left out of engagement with contacts 23^a and 24, thus opening the before-mentioned maintaining circuit and permitting the lever 19 to fall back to right-hand position as by the action 95 of gravity on the armature 22. This will interrupt the circuit to the motor, part of which was formed by the lever 19, thus causing the motor to stop, and when the trolley wheel passes beyond the said third contactor, its lever 28^a will drop, separating the movable contact 28^c from the stationary contact 28^b, thus breaking the circuit which energizes the relay 27, and this will release the armature 26, so that gravity may draw 100 it downward, throwing the lever 25 into its normal position, in which it is in engagement with the contacts 23^a and 24.

Thus the switch will have been thrown so as to send the car to the straight track, and 110 then all the parts will have been restored to the normal position shown in Fig. 1.

Assuming now that the motorman wishes to set the switch for the curve, and that the switchpoint is set either for the straight track or for the curve: He will approach the first contactor with the current on in 115 the motors of the car, (Fig. 4) and as the trolley wheel passes under the insulated section 1 (the latter being insulated from the trolley wire) and the trolley wheel being held by said insulated section out of contact with the trolley wire, the current, which will be fed through the motors of the car, will come from the trolley wire, through fuse 69, 120 wire 70, contact 23^a, lever 25, contact 24, wire 71, wire 77, contact 17, lever 19, contact 18, wire 78, contact 10, wire 79, relay 21, wire 80, wire 81, to the insulated section 1, and thence through the trolley wheel, trol- 130

ley pole, car, motors, track, rails, and to ground. This will cause relay magnet 21 to attract armature 20 and to raise the latter and throw the lever 16 into engagement with the vertical row of contacts. Relay magnet 21 is so designed as to require a larger current to attract armature 20 than will be furnished by a car passing under the first contactor with its current off. In winter time, for example, the heaters and lights in a car might draw approximately 18 amperes, and in such case the current required to energize relay magnet 21 must be sufficiently in excess of 18 amperes to prevent the energizing of said relay magnet when the car passes under the first contactor with its current off. Lever 16 will be held in contact with the vertical row of contacts by what may be termed a maintaining current, the purpose of the maintaining current being to hold the lever 16 in vertical position after the trolley wheel has passed from under the insulated section 1 and while the trolley wheel is passing to engagement with the third contactor. The said maintaining circuit is from the trolley wire, through the fuse 69, wire 70, contact 23^a, lever 25, contact 24, wire 71, contact 11, lever 16, contact 10, wire 79, relay magnet 21, wires 80 and 82, to contact 13, lever 16, contact 14, wire 82^a, wire 66, resistance 67, to ground 68.

While the lever 16 is thus being held in engagement with the vertical row of contacts a circuit is completed to the switch operating motor, sending the current in the opposite direction through the armature of the motor from that previously described, thus causing the motor to rotate in the opposite direction. The said circuit is as follows:

From the trolley wire, through the fuse 69, wire 73, resistance 74, wire 83, wire 84, contact 9, lever 16, contact 8, wire 34, armature 30, wire 32, contact 6, lever 16, contact 7, wire 36, fields 35 of the motor, and to ground 37. This will operate the motor and throw the switch for the curve, if the switch is not already so thrown. The motor will continue to revolve, after it has thrown the switch, until the trolley wheel reaches the third contactor, when the circuit will be completed through the relay magnet 27 to attract the armature 26 and disengage the lever 25 from the contacts 23^a and 24, as described in the first instance, interrupting the maintaining circuit to relay 21, and allowing the lever 16 to fall by gravity to its normal retracted position, the movement of the lever 16 opening the circuit in the motor and causing the motor to cease to revolve. Thus all the levers 16, 17, and 25 will have been restored to normal position, as shown in Fig. 1.

It will be observed that in the first instance, when the motorman passes under the insulated section 1, with the motor current

off, no current flows through the relay apparatus until the trolley wheel raises the lever 2^a of the second contactor, when the current flows through the relay apparatus from the trolley wire toward the right, so 70 to speak. If a following car should pass under insulated section 1 with its current on, before the preceding car passed the third contactor and restored the parts to normal position, no effect would be produced, as lever 75 19 is in vertical position thereby preventing the energizing of relay 21, since the circuit to said relay is broken at contacts 17 and 18. When the motorman passes under the insulated section 1 with the motor current 80 on and the parts in normal position, the current flows from the trolley wire, through the relay apparatus to the left, so to speak, and thence through the insulated section and the car to the ground. As this action, however, 85 throws the lever 16 to vertical position and disengages it from the contacts 4 and 15, it interrupts the circuit which would otherwise have been completed through contacts 4 and 15 to relay 23 when the trolley wheel 90 passed under the lever 2^a, so that the raising of the said lever by the trolley wheel produces no electrical effect. The same non-action will result if a following car passes under the second contactor before the preceding 95 car passes under the third contactor and returns the parts to normal position. Thus, when the trolley wheel passes under the first and second contactors with the motor current on, the first contactor acts and the second 100 is rendered inoperative. When the trolley wheel passes under the first and second contactors, with the motor current off, the first contactor is rendered inoperative and the second operative. The action is the same 105 if a following car passes under the first or second contactor before the preceding car passes under the third contactor and returns the parts to normal position. In other words, in the present embodiment, each lever 110 when in normal position forms part of the circuit necessary to move the other lever thereby forming what may be termed an interlocking action. When one lever has been moved, therefore, the other lever cannot be 115 moved until the first lever returns to normal position, which occurs only when the car passes under the third contactor.

I claim:—

1. In an electric switch operating mechanism, the combination of a switch, a motor for throwing the same, a device for controlling current to operate said motor in one direction, a device for controlling current to operate said motor in the opposite direction, 120 a current conductor for the car motor current, and separate contactors connected with said conductor for operating said devices.

2. In an electric switch operating mecha- 130

nism, the combination of a switch, a motor for throwing the same, a device for controlling current to operate said motor in one direction, a device for controlling 5 current to operate said motor in the opposite direction, a current conductor for the car motor current, and separate contactors connected with said conductor for operating said devices, one of said contactors being operable by a conductive contact of a trolley, the other of said devices being operable by mechanical pressure of a trolley.

3. In an electric switch operating mechanism, the combination of a switch, a motor 15 for throwing the same, a device for controlling current to operate said motor in one direction, a device for controlling current to operate said motor in the opposite direction, a current conductor for the car motor current, and separate contactors connected with 20 said conductor for operating said devices, one of said contactors being operable by a conductive contact of a trolley, the other of said devices being operable by mechanical 25 pressure of a trolley, said devices being located in sequence along said conductor.

4. In an electric switch operating mechanism, the combination of a switch, a motor for throwing the same, a device for controlling 30 current to operate said motor in one direction, a device for controlling current to operate said motor in the opposite direction, a current conductor for the car motor current, and separate contactors connected with 35 said conductor for operating said devices, one of said contactors being operable by a conductive contact of a trolley, the other of said contactors being operable by mechanical pressure of a trolley, the circuit of each of 40 said contactors including in it a part of the motor controlling device of the other contactor when said device is at rest.

5. In an electric switch operating mechanism, the combination of a switch, a motor 45 for throwing the same, two motor controlling devices, one for operating the motor in one direction and the other for operating the motor in the opposite direction, contactors for said devices mounted on the car 50 motor current conductor, one of said contactors comprising a section insulated from said conductor, the other of said contactors comprising a device operable by mechanical pressure, a trolley, means for operating each 55 of said motor controlling devices, each of said means being in circuit with one of said contactors and with the car motor current conductor.

6. In an electric switch operating mechanism, the combination of a switch, a motor 60 for throwing the same, two motor controlling devices, one for operating the motor in one direction and the other for operating the motor in the opposite direction, contactors 65 for said devices mounted on the car

motor current conductor, one of said contactors comprising a section insulated from 70 said conductor, the other of said contactors comprising a device operable by mechanical pressure, a trolley, means for operating each of said motor controlling devices, each of said means being in circuit with one of said contactors and with the car motor current conductor, each of said circuits comprising the motor controlling device of the 75 opposite contactor.

7. In an electric switch operating mechanism, the combination of a switch, a motor for throwing the same, controlling devices for operating said motor in opposite directions, means for operating said motor controlling device, a contactor in circuit with one of said means and the car motor current conductor, said contactor comprising a section mounted upon but insulated from 80 said motor current conductor, a contactor in circuit with the other of said means and with said motor current conductor, said last named contactor comprising a device operable by the pressure of a trolley.

8. In an electric switch operating mechanism, the combination of a switch, a motor for throwing the same, motor controlling devices for operating said motor in opposite directions, means for operating said motor controlling devices, a contactor in circuit with one of said means and the car motor current conductor, said contactor comprising a section mounted upon but insulated from 90 said motor current conductor, a contactor in circuit with the other of said means and with the motor current conductor, said last named contactor comprising a device operable by the pressure of a trolley, one of said contactors being in advance of the other of said contactors relative to the movement of the trolley.

9. In an electric switch operating mechanism, the combination of a switch, a motor for throwing the same, motor controlling devices for operating said motor in opposite directions, means for operating said motor controlling devices, a contactor in circuit with one of said means and the car motor current conductor, said contactor comprising a section mounted upon but insulated from 100 said motor current conductor, a contactor in circuit with the other of said means and with the motor current conductor, said last named contactor comprising a device operable by the pressure of a trolley, one of said contactors being in advance of the other of said contactors relative to the movement of the trolley.

10. In an electric switch operating mechanism, the combination of a switch, a motor for throwing the same, motor controlling devices for operating said motor in opposite directions, means for operating said motor controlling devices, a contactor in circuit 110

- with one of said means and the car motor current conductor, said contactor comprising a section mounted upon but insulated from said motor current conductor, a contactor in 5 circuit with the other of said means and with the motor current conductor, said contactor comprising a device operable by the pressure of a trolley, one of said contactors being in advance of the other of said contactors relative to the movement of the trolley, the circuit of each of said contactors comprising the motor controlling device of the other contactor when in a retracted position.
- 15 11. In an electric switch operating mechanism, the combination of a switch, a motor for throwing the same, motor controlling devices for operating said motor in opposite directions, means for operating said motor 20 controlling devices, a contactor in circuit with one of said means and the car motor current conductor, said contactor comprising a section mounted upon but insulated from said motor current conductor, a contactor in 25 circuit with the other of said means and with the motor current conductor, said contactor comprising a device operable by the pressure of a trolley, one of said contactors being in advance of the other of said contactors relative to the movement of the trolley, and a maintaining circuit for each of 30 said motor controlling devices, said circuit comprising conductors leading from the motor conductor to the ground, comprising the corresponding motor controlling device, and also comprising another contact device, 35 means for operating said last mentioned contact device, and a third contactor on the motor current conductor for operating said 40 last mentioned means.
12. In an electric switch operating mechanism, the combination of a switch, a motor for throwing the same, motor controlling devices for operating said motor in opposite 45 directions, means for operating said motor controlling devices, a contactor in circuit with one of said means and the car motor current conductor, said contactor comprising a section mounted upon but insulated from 50 said motor current conductor, a contactor in circuit with the other of said means and with the motor current conductor, said contactor comprising a device operable by the pressure of a trolley, one of said contactors being in advance of the other of said 55 contactors relative to the movement of the trolley, and a maintaining circuit for each of said motor controlling devices, said circuit comprising conductors leading from the 60 motor conductor to the ground, comprising the corresponding motor controlling device and also comprising another contact device, means for operating said last mentioned contact device, and a third contactor on the 65 motor current conductor for operating said

last mentioned means, said third contactor comprising an electric switch adapted to be operated by pressure of the trolley.

13. In an electric switch operating mechanism, the combination of a switch, a motor 70 for throwing the same, motor controlling devices for operating said motor in opposite directions, means for operating said motor controlling devices, a contactor in circuit with one of said means and the car motor 75 current conductor, said contactor comprising a section mounted upon but insulated from said motor current conductor, a contactor in circuit with the other of said means and with the motor current conductor, said contactor comprising a device operable by the pressure of a trolley, one of said contactors being in advance of the other of said contactors relative to the movement of the trolley, and a maintaining circuit for each of 80 said motor controlling devices, said circuit comprising conductors leading from the motor conductor to the ground, comprising the corresponding motor controlling device, and also comprising another contact device, 85 means for operating said last mentioned contact device, and a third contactor on the motor current conductor for operating said last mentioned means, said third contactor comprising an electric switch adapted to be 90 operated by pressure of the trolley, said means for operating said last mentioned device comprising a magnet adapted to disengage said third contact device, and a connection from said third contactor through 95 said magnet to ground.

14. In an electric switch operating mechanism, the combination of a track switch, a motor for throwing said switch, means to operate said motor in one direction comprising 100 a first lever adapted to be moved to close a circuit to said motor, means to operate said motor in the opposite direction comprising a second lever adapted to be moved to close a circuit to said motor, and means to move 110 each lever comprising a circuit closed through the other lever when said other lever is in normal position and opened when said other lever is in position to close a circuit to said motor.

15. In an electric switch-operating mechanism, the combination of a track switch, a motor for throwing said switch, means to operate said motor in either direction comprising two sets of contacts normally closed, 120 and means comprising contact levers to open one of said sets of contacts when the motor is rotated in one direction and to open the other of said sets of contacts when the motor is rotated in the opposite direction.

16. In an electric switch operating mechanism, the combination of a track switch, a motor for throwing the same, means for operating said motor and connections between said motor and said switch comprising a 130

rack and a lever actuated thereby, such that after the motor has thrown the switch, said connections shall be disconnected, whereby the switch may be thrown by hand.

5 17. In an electric switch operating mechanism, the combination of a switch, a motor for throwing the same, and mechanism connecting said motor with said switch comprising a rack and a lever actuated thereby, 10 said motor being disconnected from said mechanism at each end of its throw.

15 18. In an electric switch operating mechanism, the combination of a switch, a motor for throwing the same, and mechanism connecting said motor with said switch, said mechanism having a lost-motion connection with said switch comprising a sleeve slidable longitudinally before engagement.

20 19. In an electric switch operating mechanism, the combination of a switch, a motor for throwing the same, and mechanism connecting said motor with said switch, said motor being disconnected from said mechanism at each end of its throw, said mechanism comprising two parts having lost-motion 25 between them.

30 20. In an electric switch operating mechanism, the combination of a switch, a motor for throwing the same, and mechanism connecting said motor with said switch, said motor being disconnected from said mechanism at each end of its throw, and said mechanism having a lost motion connection with said switch.

35 21. In an electric switch operating mechanism, the combination of a switch, a motor for throwing the same, and mechanism connecting said motor with said switch, said motor being disconnected from said mechanism at each end of its throw, said mechanism having a lost-motion connection with said switch, and said mechanism comprising two parts having a lost-motion connection between them.

45 22. In an electric switch operating mechanism, the combination of a switch, a motor for throwing the same, and mechanism connecting said motor with said switch, said motor being disconnected from said mechanism at each end of its throw, said parts being so constructed that the load between the motor and the switch shall be picked up by the motor in successive portions.

50 23. In an electric switch operating mechanism, the combination of a track switch, a motor for throwing the same, and connections comprising a worm driven by the motor and a rack engaged by said worm, said

rack being permitted to travel far enough to pass out of engagement with said worm at 60 each end, and means yieldingly holding the respective end teeth of said rack against said worm.

65 24. In an electric switch operating mechanism, the combination of a track switch, a motor for throwing the same, and connections comprising a worm driven by the motor and a rack engaged by said worm, said rack being permitted to travel far enough to pass out of engagement with 70 said worm at each end, and means yieldingly holding the respective end teeth of said rack against said worm, said means comprising a weighted lever having an arm adapted to engage shoulders on said rack. 75

80 25. In an electric switch operating mechanism, the combination of a track switch, a motor for throwing the same, a part carrying a pin, adapted to be reciprocated by said motor, an oscillating arm connected with the switch and adapted to be engaged by said pin, the relative length of said arm and travel of said pin being such that said pin passes out of engagement with said arm at each end of its stroke, and means for throwing said arm back in the path of said pin. 85

90 26. In an electric switch operating mechanism, the combination of a track switch, a motor for throwing the same, a part carrying a pin, adapted to be reciprocated by said motor, an oscillating arm connected with the switch and adapted to be engaged by said pin, the relative length of said arm and travel of said pin being such that said pin passes out of engagement with said arm at each end of its stroke, and means for throwing said arm back in the path of said pin, and means comprising shoulders carried by said arm, and a counter-balanced finger adapted to engage said shoulders. 95

100 27. In an electric switch operating mechanism, the combination of a switch, a motor for throwing the same, means for controlling said motor, mechanism connecting said motor with the switch, and means whereby said motor becomes disconnected from said mechanism when the switch has been thrown comprising a rack and a lever actuated thereby.

105 In testimony that I claim the foregoing 110 I have hereunto set my hand.

ROY VINSON COLLINS.
